J. L. FOLSOM.

CARPET.

No. 18,139.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,139, dated March 6, 1888.

Application filed January 26, 1888. Serial No. 262,062. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of a succession of small leaf and fruit forms with a connecting branch

or stem work, the leaf forms being repeated in close proximity over the face of the carpet, as shown. The leaf forms resemble oak-leaves 20 in general character and are connected together by short stems in small clusters, these clusters being supported on longer stems or branches. From the larger stems or branches project smaller stems or twigs carrying acorn-shaped 25 forms, either in clusters or singly.

What I claim as new, and desire to secure by Letters Patent, is—

The design for carpets, consisting of the design substantially as shown.

JAS. L. FOLSOM.
